UNITED STATES PATENT OFFICE

157,472

CALENDAR CASE

Gerald Drazan, Spokane, Wash.

Application October 4, 1948, Serial No. 148,966

Term of patent 14 years

(Cl. D74—5)

To all whom it may concern:

Be it known that I, Gerald Drazan, a citizen of the United States, residing at Spokane, in Spokane County, and State of Washington, have invented a new, original, and ornamental Design for a Calendar Case, of which the following is a specification, reference being had to the accompanying drawing, forming a part thereof.

Fig. 1 is a front perspective view of a calendar case, showing my new design; and

Fig. 2 is a rear perspective view thereof.

I claim:

The ornamental design for a calendar case, as shown.

GERALD DRAZAN.
